UNITED STATES PATENT OFFICE.

FRANK H. WAGGONER, OF CHICAGO, ILLINOIS, ASSIGNOR TO COMMERCIAL COLORTYPE COMPANY, OF CHICAGO, ILLINOIS, A CORPORATION OF ILLINOIS.

FOLDING FAN.

1,231,105.

Specification of Letters Patent. Patented June 26, 1917.

Application filed November 18, 1916. Serial No. 132,128.

To all whom it may concern:

Be it known that I, FRANK H. WAGGONER, a citizen of the United States, residing at Chicago, in the county of Cook and State 5 of Illinois, have invented certain new and useful Improvements in Folding Fans, of which the following is a specification.

My invention relates to a fan foldable into a thin, flat, mailable parcel suitable, for 10 example, for advertising purposes; and the object of the invention is to provide a device of this type which will be easily folded and unfolded, slightly in appearance, durable, and inexpensive to manufacture and in 15 which the foldable handle will be retained in its unfolded position with respect to the body of the fan as against incidental disturbances when the fan is used.

This application is a continuation, in part, 20 of my co-pending application Serial No. 117,964, filed August 31, 1916 with respect, particularly, to the form of the invention shown in Figures 6 and 7 of the drawing of that application.

25 The invention is illustrated, in certain preferred embodiments, in the accompanying drawings wherein

Fig. 1 is a view, in perspective, of one 30 form of the invention showing the device unfolded.

Fig. 2 is a similar view of a modified construction showing the fan body sections unfolded but the handle folded.

Fig. 3 is a similar view of the fan shown 35 in Fig. 2 but with the handle in the position of use.

Fig. 4 is a detail section on line 4—4 of Fig. 3.

Figs. 5 and 6 are views corresponding to 40 Figs. 2 and 3 illustrating another modification, and

Fig. 7 is a sectional view taken on line 7—7 of Fig. 6.

Like characters of reference indicate like 45 parts in the several figures of the drawings.

Referring first to Fig. 1, the fan body 50 consists of a sheet of relatively stiff material such, for example, as cardboard, which is folded along line 11 to provide two sections 12, 13, which are foldable one upon the other. 14 is a handle which may consist of a thin strip of wood, the handle being preferably shorter than the width of the fan body. The handle is pivotally secured to 55 section 12 at a fixed point thereon by means

of an eyelet 15, or other suitable means. The section 13 is formed with a curved slot 16 which provides a tab 17 adapted to overlie the end of handle 14 when the latter is turned to the position of use. The dotted 60 lines indicate the position of the handle when the device is folded, for mailing, for example. Section 13 will, in such case, be folded over upon section 12 so that the handle will lie between the sections and the 65 latter may be held together by a paper clip, or other suitable means.

If the material of the fan body is sufficiently stiff and heavy the engagement provided by tab 17 is adequate to hold the 70 handle in the position of use. When thinner, more flexible stock is used, I prefer to modify slightly the arrangements providing the engagement for the inner end of the handle. For example, in Figs. 2, 3 and 4 75 the section 13^a is provided with two preferably curved slits 18, 19, which together provide a retaining band 20 for the end of the handle 14^a. The portion 21 of slit 19 provides a stop for one edge of the handle as 80 shown in Figs. 3 and 4. Preferably the extremities 22 of the slits are deflected from the line of the main portions of the slits so as to resist the tendency of the retaining band to tear out. It will be seen that this 85 arrangement, which involves making only two slits in the section across the fold from the pivot, provides an effective engagement for the upper end of the handle which holds the handle in place when the fan is in use. The 90 fan body is severed in such manner that there are no projections formed likely to bend out or tear off. The two slits provide the entire means for retaining the end of the handle including the stop for one edge 95 of the same, checking turning of the handle on its pivot. After the handle has been forced under the retaining band 20 the edge 21 necessarily springs back against the edge of the handle so as to provide automatically 100 a positive stop for the handle preventing it from turning on its pivot until released. This stop is at the extremity of the handle.

A slightly different arrangement is shown in Figs. 5, 6 and 7. In this form of the 105 invention the fan section 13^b is provided with a pair of substantially parallel slits 23 arranged at right angles to the line of fold 11^b. These slits are connected by a curved slit 16^b. This arrangement provides two tabs 24, 25, 110

one of which lies in front of and one back of the end of the handle 14^b. The tabs are slightly displaced from the plane of the fan body when the handle is unfolded. The 5 slits 23, 23 provide stops for the edges of the handle, checking the tendency to displacement of the handle in either direction from the position of use.

It will be understood that while my invention is described in certain preferred embodiments it is not to be considered as limited to the precise details of construction shown and described, except so far as the claims are expressly so limited.

15 I claim:

1. In a fan, the combination of a body portion comprising two sections foldable one upon the other, and a handle pivotally connected to one of said sections at a fixed 20 point and adapted to extend across the line of fold between the sections; the section on the other side of said line of fold from the pivotal connection being formed with a curved slit which permits a part of said 25 fan body to overlap the end of the handle.

2. In a fan, the combination of a body portion comprising two sections foldable one upon the other, and a handle pivotally connected to one of said sections at a fixed 30 point and adapted to extend across the line of fold between the sections; the section on the other side of said line of fold from the pivotal connection being formed with a pair 35 of curved slits providing a retaining band for the end of the handle.

3. In a fan, the combination of a body portion comprising two sections foldable one upon the other, and a handle pivotally connected to one of said sections at a fixed 40 point and adapted to extend across the line of fold between the sections; the section on the other side of said line of fold from the pivotal connection being formed with a pair 45 of curved slits providing a retaining band for the end of the handle, and a stop for one edge of the same which resists the tendency of the handle, when unfolded, to turn on its pivot.

4. In a fan, the combination of a body 50 portion comprising two sections foldable one upon the other, and a handle pivotally connected to one of said sections at a fixed point and adapted to extend across the line of fold between the sections; the section on the other side of said line of fold from the 55 pivotal connection being formed with a pair of slits providing a retaining band for the end of the handle, the extremities of which slits are deflected out of line with the

rest of the slits to check the tendency of the 60 fan body to tear.

5. In a fan, the combination of a body portion comprising two sections foldable one upon the other, and a handle pivotally connected to one of said sections at a fixed 65 point and adapted to extend across the line of fold between the sections; the section on the other side of said line of fold from the pivotal connection being formed with a curved slit and adjacent thereto with another slit which together provide a retaining band for one end of the handle, and a stop for the edge thereof.

6. In a fan, the combination of a body portion comprising two sections foldable 75 one upon the other, and a handle pivotally connected to one of said sections at a fixed point and adapted to extend across the line of fold between the sections; the section on the other side of said line of fold from the pivotal connection being formed with a curved slit and adjacent thereto with another slit which together provide a retaining band for one end of the handle, and a stop for the edge thereof. 80 The extremities of said slits being deflected from the main portion of the slits for the purpose of preventing the tearing of the material at these places.

7. In a fan, the combination of a body portion comprising two sections foldable 85 one upon the other, and a handle pivotally connected to one of said sections at a fixed point and adapted to extend across the line of fold between the sections; the section on the other side of said line of fold from the pivotal connection being provided with a curved retaining band for the end of the 90 handle.

8. In a fan, the combination of a body portion comprising two sections foldable 100 one upon the other, and a handle pivotally connected to one of said sections at a fixed point and adapted to extend across the line of fold between the sections; the section on the other side of said line of fold from the pivotal connection being provided with a curved retaining band for the end of the 105 handle which forms a stop for one edge of the same.

9. In a fan, the combination of a body 110 portion comprising two sections foldable one upon the other, and a handle pivoted to one of said sections at a fixed point and adapted to interlock with the other section by engagements which resist the movement 115 of the handle from the position of use.

FRANK H. WAGGONER.
